LIQUID DISPENSING NOZZLE

Filed Jan. 21, 1932

INVENTOR:

JOSEPH C. WOODFORD,

BY *Arthur E. Raigg,*
Attorney.

UNITED STATES PATENT OFFICE

JOSEPH C. WOODFORD, OF ARDMORE, PENNSYLVANIA, ASSIGNOR TO SERVICE STATION EQUIPMENT COMPANY, OF CONSHOHOCKEN, PENNSYLVANIA, A CORPORATION OF DELAWARE

LIQUID DISPENSING NOZZLE

Application filed January 21, 1932. Serial No. 587,899.

My invention relates to nozzles particularly adapted for dispensing gasoline under control of a valve in the nozzle, which valve is normally closed by a spring and pressure of the liquid to be dispensed through the nozzle but adapted to be manually opened by a lever fulcrumed on the nozzle. In such nozzles valves, more power is required to initially lift the valve from its seat and to prevent its too sudden closure under the combined pressure of the valve spring and the compressed liquid than is required to move it throughout the other portion of its range of movement; and it is desirable to effect both the closure and the unseating of the valve and displacement thereof to wide open position with the minimum amount of movement of the lever and exertion on the part of the operator. Ordinarily, such nozzle valve operating levers are of constant leverage; the fulcrum thereof being fixed with respect to the nozzle. However, such construction and arrangement is disadvantageous in that if the leverage is such as to permit the operator to apply the power necessary to unseat the valve and control its closure without fatigue, the range of movement to displace the valve to wide open position is greater than can be conveniently repeatedly effected by the operator without fatigue. Therefore, my invention provides such a valve with an operating lever of the second order having its fulcrum end so shaped that in its normal idle position with the valve closed, the fulcrum point is closer to the valve operating stem to which the power is to be applied than when the valve has been displaced by said lever to its wide open position; the arrangement being such that the distance of the fulcrum from the axial line of said stem increases from the beginning to the end of the valve opening movement of said lever.

The effect of that arrangement is that greater leverage is afforded at the beginning of said opening operation to facilitate the displacement of the valve against the combined pressure of its spring and the liquid than during the subsequent opening movement, and such subsequent opening move-

ment is effected with less leverage and consequent greater proportion of movement of the stem with respect to the movement of the lever than at the beginning of said operation. Consequently, such construction and arrangement is advantageous in that it permits the operation of the valve with the minimum amount of fatigue of the operator. 55

In the form of my invention chosen for illustration, the lever is provided with a guide pin engaging in a guide slot in the nozzle frame extending parallel with the axis of the valve stem to prevent longitudinal displacement of the lever, and the fulcrum end thereof, local to said pin, is in fact a curved cam, different points of the periphery of which successively contact with said frame as fulcrum points progressively receding from the axis of the valve stem. 60 65

My invention includes the various novel 70 features of construction and arrangement hereinafter more definitely specified.

In said drawing; Fig. I is a fragmentary plan view of a nozzle conveniently embodying my invention, the tubular discharge end 75 thereof being broken away.

Fig. II is a fragmentary vertical sectional view taken on the line II, II, in Fig. I in the direction of the arrow marked thereon.

Fig. III is a fragmentary sectional view 80 taken on the line III, III, in Fig. II, showing the construction and arrangement of the lever guide pin and the slotted portion of the nozzle frame in which it is engaged. 85

In said figures, 1 is the tubular nozzle casing, conveniently formed of cast bronze, having the wrought metal conduit 2 of any convenient length and shape rigidly connected therewith by the screw thread 3 and solder joint 4. 90

Said casing 1 has the valve seat 6 for the valve 7 which conveniently includes the annular body 8 of resilient material which is slightly compressible on said seat. Said annular body 8 is detachably connected with the stem 9 by the nut 10; so that it may be renewed when worn. The inner end of said stem 9 is mounted to reciprocate in the bearing 12 in the screw cap 13 which is removably 100

fitted in said casing 1. Said cap forms an abutment for the spring 14 which bears upon said valve 7 continually tending to close it in the same direction it is pressed by the liquid 5 which is to be dispensed through said nozzle in the direction of the arrow shown in Fig. II.

The outer end of said stem 9 is mounted to reciprocate in the stuffing box 16 which has the screw thread 17 rigidly engaging said 10 nozzle 1. Said stuffing box is conveniently inserted through the valve seat 6 and has its inner end transversely slotted at 18 for engagement with a wrench by which it is set in the position shown. Said stuffing box includes the packing 20 adjustably compressed 15 by the gland 21 carried by the screw cap 22.

The outer end of said valve stem 9 projects in cooperative relation with the valve operating lever 24 which is of the second order, 20 having its fulcrum end 25 curved as a cam for progressive fulcrum contact with the inner curved surface 26 of the guard frame 27 which is conveniently cast in integral relation with said nozzle 1.

25 As best shown in Fig III, the fulcrum end 25 of said lever 24 is bifurcated so as to extend upon opposite sides of the lug 29 on said nozzle guard frame 27, and the pin 31 which is conveniently riveted through the bifurcations 25 of said lever 24 is engaged in the slot 32 which extends in said lug 29 substantially parallel with the axis of said stem 9. I find it convenient to extend the free end 34 of said lever 24 through a slot which 30 is indicated at 35 in said nozzle guard frame 27 to maintain said lever 24 in registry with said valve stem 9 through the range of its movement from the normal idle position shown to the opposite limit of said slot 35 in 35 which said valve is opened to its fullest extent.

The effect of the construction and arrangement aforesaid is that at the initial movement of said lever 24 to lift said valve 7 from its 40 seat, the fulcrum point of contact of the lever cam surface 25 with the surface of the guard is at 37, but such fulcrum point of contact progressively shifts during the opening movement of said lever to the point 38 on 45 said lever cam end 25, with the effect that the power from the hand of the operator who grasps said nozzle 1 in his palm with his fingers extending through the space 40 between the lever 24 and said guard 27 is initially more than double the leverage at the 50 termination of the opening operation.

It is to be particularly noted that the pin 55 31 is not at any time utilized as a fulcrum for said lever 24, but merely serves to prevent longitudinal displacement of the cam shaped fulcrum end 25 of said lever with respect to the surface 26 of the frame 27 with which it cooperates, and that any other suitable means may be employed to maintain said 60 lever end in proper relation with its fulcrum

support. For instance, said fulcrum end 25 of the lever may be slotted to engage a pin which is fixed in said lug 29, for preventing longitudinal movement of said lever while permitting oscillatory movement thereof with progressive shifting of position of the fulcrum with respect to the valve stem during the movement of the valve.

70 Therefore, I do not desire to limit myself to the precise details of construction and arrangement herein set forth, as it is obvious that various modifications may be made therein without departing from the essential features of my invention, as defined in the appended claims.

I claim:

1. In a liquid dispensing nozzle; the combination with a valve for controlling the passage of liquid through said nozzle; of a lever for opening said valve; and means affording a fulcrum for said lever, whereby the fulcrum is progressively shifted to vary the effective leverage of said lever with respect to said valve throughout the opening movement of said valve by said lever; whereby the maximum leverage is afforded to initially displace the valve from its seat and diminishes as the valve is shifted away from its seat to the limit of its opening movement; wherein the lever is of the second order and its fulcrum end is curved to afford a cam surface and a frame of the nozzle affords a fulcrum support for said cam surface with respect to which the point of fulcrum contact of said lever is shifted by movement of the latter.

2. In a liquid dispensing nozzle; the combination with a valve for controlling the passage of liquid through said nozzle; of a stem on said valve mounted to reciprocate transversely to the axis of said nozzle through an opening in the latter; a guard frame on said nozzle in opposition to said stem; and a lever for operating said valve interposed between said stem and said frame, having at one end a cam surface adapted to bear on said frame as a fulcrum support; the point of fulcrum contact of said cam surface and said guard being progressively shifted during the movement of said lever to vary the effective leverage of said lever with respect to said stem; whereby the maximum leverage is afforded to initially displace the valve from its seat and diminishes as the valve is shifted away from its seat to the limit of its opening movement.

3. In a liquid dispensing nozzle; the combination with a valve for controlling the passage of liquid through said nozzle; of a lever for opening said valve; and means affording a fulcrum for said lever, whereby the fulcrum is progressively shifted to vary the effective leverage of said lever with respect to said valve throughout the opening movement of said valve by said lever; whereby the maximum leverage is afforded to initially dis-

place the valve from its seat and diminishes as the valve is shifted away from its seat to the limit of its opening movement; wherein the fulcrum end of the valve lever is bifurcated; and a lug rigidly connected with the 5 nozzle extends between the bifurcations of said lever, and there is a pin and slot connection between said lever and lug.

4. In a liquid dispensing nozzle; the combination with a valve for controlling the passage of liquid through said nozzle; of a lever 10 for opening said valve; and means affording a fulcrum for said lever, whereby the fulcrum is progressively shifted to vary the effective leverage of said lever with respect to said 15 valve throughout the opening movement of said valve by said lever; whereby the maximum leverage is afforded to initially displace the valve from its seat and diminishes as the valve is shifted away from its seat to 20 the limit of its opening movement; wherein the fulcrum end of the lever is bifurcated; and a lug rigidly connected with the nozzle extends between the bifurcations of said lever, and is provided with a slot; and a pin 25 fixed in said lever extends in said slot; whereby longitudinal movement of said lever is prevented while oscillatory movement thereof with progressive shifting of position of the fulcrum with respect to the axis of the 30 valve is permitted.

In testimony whereof, I have hereunto signed my name at Conshohocken, Pennsylvania, this eighteenth day of January, 1932.

JOSEPH C. WOODFORD.
